ELECTROPLATING MACHINE

Daniel J. Borodin, Detroit, Mich., assignor to Wagner Brothers, Inc., Detroit, Mich., a corporation of Michigan

Filed Sept. 16, 1957, Ser. No. 684,150

24 Claims. (Cl. 134—76)

This invention relates to an electroplating machine and more particularly to an electroplating machine of the automatic type wherein means are provided for automatically conveying work pieces through a succession of plating tanks.

Electroplating machines of the automatic type are generally expensive mechanisms and are usually designed with a particular plating cycle in mind. In many instances where the plating cycle is changed, various portions of the plating machine have to be re-designed and re-built to accommodate the new plating cycle.

The present invention has for its object the provision of a plating machine of the automatic type that is constructed so that the machine is adapted to accommodate different plating cycles. For example, one plating cycle might require a series of single station tanks or perhaps a single tank with four or five stations in the tank. Another plating cycle might require less single station plating tanks or less stations within a multiple station tank.

The machine of the present invention is constructed so that one or more stations along the path of travel of the work pieces may be selectively skipped by rendering certain components of the machine either operative or inoperative.

Another object of the invention resides in the provision of an electroplating machine of the automatic type wherein work pieces are transferred in an elevated position from one tank to another and wherein the work pieces are conveyed through a tank on cathode rails, the arrangement being such that the transfer distance between the adjacent stations of adjacent tanks is the same as the spacing between successive stations in a multiple station tank.

In the drawings:

Figure 1 is a fragmentary top plan view of a plating machine embodying the present invention.

Figure 2 is a sectional view taken generally along the line 2—2 in Figure 1.

Figure 3 is a fragmentary sectional view similar to Figure 2 and showing the components of the machine at a different point in the cycle of the machine.

Figure 4 is a fragmentary sectional view similar to Figure 3 showing the pusher arms in the inoperative position.

Figure 5 is a fragmentary side elevational view of the means for suspending the work pieces above the tanks at one station.

Figure 6 is a sectional view along the line 6—6 in Figure 5.

Figure 7 is a perspective view of the arrangement shown in Figure 5.

Figure 8 is a sectional view along the line 8—8 in Figure 3.

Figure 9 is a side elevational view of a portion of the machine as seen in the direction of the arrow 9 in Figure 2.

Figure 10 is a fragmentary view of the adjustable lift angles on the elevator mechanism of the machine.

Figure 11 is a fragmentary view of the fixed lift angles on the elevator mechanism of the machine.

Figure 12 is a diagrammatic view illustrating the cycle of operation of the carriage and elevator structure of the machine.

Referring to Figures 1 and 2, there is illustrated a portion of a plating machine which includes a plurality of plating tanks shown in broken lines and designated 10, 12 and 14. These tanks are arranged in a row and supported 10 on a base structure 16 comprised of structural members not shown. In Figures 1 and 2, one side of the machine is shown. The other side of the machine, not illustrated, may be constructed substantially the same as the side illustrated in these figures.

15 Along the longitudinal center line of the base 16, there is arranged an upright carriage 18 which is mounted on rollers 20 for reciprocation lengthwise of the machine. The carriage 18 is driven by a hydromotor 19. Carriage 18 is supported in an upright position by means of stationary panel members 22 mounted on base 16 and extending lengthwise along each side of carriage 18. At predetermined locations along carriage 18 there are mounted elevator housings 24 in which vertical elevator columns 26 are arranged for vertical movement. Each column 26 is

25 formed with a gear rack portion 28 which meshes with a drive gear 29 on a shaft 30 driven by a motor 32. This general arrangement of the base 16, carriage 18 with elevators 26 and the supporting panels 22 is shown and described in detail in my application Serial No. 596,712, 30 filed July 9, 1956.

Carriage 18 has mounted thereon a plurality of horizontally extending fixed brackets 34 provided with support blocks 36 at the free ends thereof. A shaft 38 extends through support blocks 36 and is supported thereby. 35 Arms 40 are pivotally supported on shaft 38 by means of bearing blocks 42. Arms 40 are spaced along shaft 38 a distance corresponding generally to the spacing between successive stations of the machine.

It will be noted that the spacing between the station A 40 at the end of tank 10 and the first station B in the tank 12 is equal to the spacing between the first station B in tank 12 and the second station C in tank 12. Likewise, the spacing between stations C and D and between D and E is equal to the spacing between stations A and B.

45 At the free end of each pusher arm 40 there is adjustably supported by means of a clamp 44 a short I-beam section 46 on which a pusher member 48 is mounted. Pusher member 48 includes a strap 50 extending transversely of the I-beam section 46 having depending plates 52 fixed at the opposite ends thereof. Each plate 52 is fashioned with a downwardly opening V-shaped notch 54 (Figure 9). The notches 54 terminate in a slot 55 arranged to interengage with work carriers 56 that are slidably supported on the cathode rails 58 that extend horizontally over and lengthwise of the plating tanks.

Each carrier 56 comprises a pair of end castings 60 having a central web portion 62 over which the V-shaped notches 54, 55 of pusher 48 are adapted to engage (Figure 2). The end castings 60 are connected by a cross bar 64, which in turn supports a hooked member 66, from which a work rack 68 is arranged to be suspended.

Carrier 56 is also provided with outwardly extending flanges 70 at opposite ends thereof and with inwardly projecting flanges 72. The carriers are adjustable lengthwise of carriage 18 by shifting the I-beam sections 46 within clamps 44. The construction of clamps 44 is shown in detail in my co-pending application Serial No. 647,522, filed March 21, 1957.

Referring now to Figure 8, it will be observed that each arm 40 is fixedly located in a direction lengthwise of the machine on shaft 38 by means of bushings 74. Thus, the arms 40 are caused to travel with the carriage

18. These arms, as pointed out previously, are journaled on shaft 38; and in the operative position shown in Figure 2, each arm 40 is maintained in a position extending horizontally over the tank by means of an adjustable stop screw 76, which engages a lug 78 on a 5 plate 80, which mounts the bearing blocks 42 on arm 40.

It will be observed that adjusting screw 76 is disposed on the opposite side of shaft 38 from pusher 48 and that screw 76 is arranged to abut against the top side of lug 78. Each arm 40 is adapted to be swung about the shaft 10 38 from the position shown in Figure 2 to the inoperative position shown in Figure 4. The arms are adapted to be locked to the carriage 18 in the inoperative position by means of a pin 80 passing through aligned openings in co-operating lugs 82 and 84 on the carriage and 15 arms respectively (Figure 4).

In the portion of the machine illustrated in Figure 1, two elevator columns 26 are shown. At their upper ends these two elevator columns are interconnected by a torque tube 86. Torque tube 86 is fixedly connected to 20 short arms 88 at the upper ends of elevator columns 26. The elevator structure for lifting the carriers 56 from rails 58 is in turn mounted on the torque tube 86. This elevator structure includes a pair of arms 90 projecting horizontally over the tanks from the opposite ends of torque tube 86.

At the outer end of each arm 90, there is adjustably mounted, as by means of a clamp 92, a vertical strut 94. Clamps 92 are constructed similarly to clamps 44. The lower ends of struts 94 are interconnected by a horizontally extending boom comprising rectangular tubes 96. At points along boom 96 corresponding to the stations A, B, C, D and E, there are mounted lift plates 98 and 30 100. The lift plates 98 adjacent opposite ends of the boom 96 are fixed while the lift plates 100 at the intermediate stations are pivotally supported, as at 102, so as to be swung from an operative position shown in solid lines in Figure 10, wherein the plates are horizontally disposed to an inoperative position shown in broken lines, where the plates extend generally vertically. Similar lift plates 98, 100 are mounted on the torque tube 40 86 at points diametrically opposite the lift plates on the boom 96 by means of vertical struts 104.

As is shown in Figure 2, each pusher arm 40 is provided at its inner end with a cylindrical lug 106. Above 45 each lug 106 there is mounted on torque tube 86, by means of brackets 107, a vertically adjustable depending stop member 108. When the elevator structure descends, the stops 108 engage the lugs 106 to pivot arms 40 upwardly to the position shown in Figure 3, wherein 50 the pusher members 48 are elevated to a position above the carriers 56.

The skip station feature of the present invention is illustrated in Figures 1, 2, 5 and 6. Adjacent the outer side of tank 12, there is fixedly mounted a pair of upright columns 110, each of which has an inwardly extending arm 112 at its upper end. The free ends of arms 112 support a boom 114, which extends longitudinally over tank 12 generally along the center line of this tank. 55

At the stations B, C and D, there is mounted on boom 114 a shuttle plate assembly 116. This shuttle plate assembly includes support members 118 and 120, depending from boom 114, which support a slide plate 122 having gibs 124 thereon forming a guide-way 126. Within guide-way 126 there is arranged a slide block 128 which supports a shuttle plate 130. At the opposite ends of guide-way 126 there are arranged stops 132 for limiting the sliding movement of shuttle plate 130. This arrangement enables each shuttle plate 130 to be shifted from an operative position in vertical alignment with the 60 corresponding station to an inoperative position out of alignment with the corresponding station.

In Figure 1, the shuttle plates 130 at stations B and C are shown in the operative position, and the shuttle plate 130 at station D is shown in the inoperative position.

Referring to Figure 2, it will be observed that the outer flanges 70 of carrier 56 are arranged to be engaged by the lift plates 98 or 100 while the inner flanges 72 are arranged to be engaged by the shuttle plates 130. It will also be observed that in the uppermost position of the elevator the flanges 72 of the carriers engaged by the lift plates 98 or 100 are spaced above the plane of the lift plates 130.

The cycle of the machine is shown diagrammatically in Figure 12. The rectangle shown here represents the path of travel of each of the elevator lift plates. The direction of feed of the work through the machine is from left to right in Figure 1 and in Figure 12.

Starting at the point M and assuming that the elevator is in the lowered position, the carriage is retracted through the distance *a* to the point N. This distance corresponds to the distance between successive stations when the carriage reaches the point N, and the elevator structure is actuated to raise the lift plates 98, 100 to the point O. The distance *b* represents the vertical travel of the lift plates. The carriage then moves forwardly through the distance *c*, which is equal to the distance *a*, to move the lift plates to the point P. Thereafter, the elevator structure is actuated to lower the lift plates through the distance *d*, which is equal to the distance *b*, and thereby again position the lift plates at the starting position M. In Figures 1 and 2, the carriage is illustrated at the position O in its cycle.

In describing the operation of this machine, let us assume that it is desired to transfer each work carrier and the rack supported thereby, from the station A in tank 10 to the station B in tank 12 and that it is desired to lower each carrier into tank 12 at the station D and thereafter push the work rack through the tank 12 to the station E and then transfer the work rack from tank 12 to tank 14. With this cycle of operation, and with the carriage in the position illustrated, the lift plates 100 at stations B and C are pivoted to the operative position. The shuttle plates 130 at stations B and C are shifted to the operative position, and the pusher arms 40 adjacent stations B and C are swung to the inoperative position shown in Figure 4.

Now, assuming, as pointed out previously, that the carriage and elevator are at the point O in the cycle illustrated in Figure 12, then a carrier 56 elevated from the end of tank 10 is supported by the lift plates 98 in an elevated position at station A. As the carriage moves forwardly to the point P, the carrier 56, supported by stationary lift plates 98, is shifted to the station B. Now, when the elevator is lowered, the carrier 56, by reason of the flanges 72, hangs on the shuttle plate 130 at station B while the lift plates 98 lower to the position M. The carriage then retracts to the position N so that the lift plates 98 are again located at station A.

If another work carrier has advanced to station A, this latter work carrier will be elevated when the elevator structure is again raised. At the same time, the lift plates 100b are located at the station B. When the elevator structure is raised, these lift plates 100b engage the flanges 70 of the work carrier hung on shuttle plate 130 at station B and lift the carrier off the shuttle plate. Then, when the carriage advances, this carrier is moved to a position in alignment with the shuttle plate 130 at the station C. The carrier is deposited on this shuttle plate when the elevator structure is lowered.

In the next cycle of the machine, the carrier hung from the shuttle plate 130 at station C is transferred by the lift plates 100c over the tank 12 to the station D. Since the shuttle plate 130 at station D is in the inoperative position, when the elevator structure is lowered, that is, during travel of the lift plates 100c from the point P to the point M, the carrier supported thereby is deposited on the cathode rails 58.

At this point in the cycle, it will be realized that the pusher arm 40d is actually located at station E. When

the elevator structure is lowered, the adjustable stop 108 engages the lug 106 on pusher arm 40d to pivot the pusher arm 40d to the position shown in Figure 3. Thereafter, when the carriage retracts from the point M to the point N in its cycle, the pusher member 48 on arm 40d is shifted to a position directly above the carrier at station D that is supported on the rails 58. The elevator structure then raises to the elevated position and in so doing the stop 108 moves upwardly out of engagement with lug 106 so that the V-shaped notches 54, 55 on the end plates 52 of the pusher 48 engage over the web portions 62 of the carriers 56. Then, as the carriage moves from the point O to the point P in its cycle, the carrier at station D is pushed along the rails 58 from the station D to the station E.

It will be observed that since the lift plates 100d are pivoted to the inoperative position there will be no interference between these lift plates and the outer flanges 70 on the carrier 56.

In the next cycle of the machine, the carrier located on the rails at the station E will be picked up by the stationary lift plates 98 at the other end of the elevator boom and transferred to the first station in the next adjacent tank 14.

Thus, it will be seen that I have provided a plating machine which is designed to accommodate different plating cycles. With the arrangement described, any station or any group of stations can be skipped or rendered operative, that is, at any station or at any group of stations the carriers can be retained in an elevated position or lowered onto the cathode rails. In addition, the machine of the present invention, by utilizing the form of pushers 48 illustrated, insures that the work will be moved through the same distance whether being pushed from one station within a tank to another station within the tank or whether being transferred in an elevated position from one station to the next station.

The V-shaped notches 54 in the end plates 52 serve to accurately locate the carriers at each station. In addition, since there is no lost motion between the pushers 48 and the carriers 56 moved thereby, that is, since the carriers 56 move as a unit with the pushers 48, there is no impact between the pushers and the carriers which would tend to jar pieces loose from the work racks 68. The pushers and the carriers move forwardly at the same instance, thus the velocity of the pusher 52 can be relatively high without much danger of pieces being jarred off the work rack.

I claim:

1. In a machine for conveying work pieces with an intermittent motion along a generally straight path by means of rail supported carriers, the combination comprising, a carriage, means for reciprocating the carriage in a direction generally parallel to said path of travel of the work pieces, said carriage having a plurality of laterally extending arms thereon and movable with the carriage, pushers mounted on and movable with said arms, said arms being journaled on the carriage for pivotal movement in a generally vertical plane so that the pushers are shifted vertically when the arms are pivoted, said pushers having carrier engaging means thereon movable into and out of engagement with the rail supported carriers in response to vertical movement of the pushers, said carrier engaging means when engaged with said carriers providing a direct driving connection between the pushers and the carriers whereby to advance the carriers along the rails when the carriage moves through its stroke in one direction, and displaceable means operatively connected with said arms for actuating the same, said displaceable means being timed with the reciprocation of the carriage for swinging said arms in one direction to engage the pushers with the carriers at one end of the carriage stroke and for swinging said arms in the opposite direction to disengage the pushers from the carriers at the other end of the carriage stroke.

2. A machine as called for in claim 1 wherein said arms are pivoted on said carriage for movement in a plane extending transversely of the line of reciprocation of the carriage.

3. A machine as called for in claim 1 wherein said carrier engaging means and the portions of the carriers engaged thereby comprise generally vertically extending lug and socket members which interfit one into the other when the pushers are moved downwardly toward the carriers.

4. A machine as called for in claim 1 wherein said carrier engaging means comprises a member on said pusher having a downwardly opening V-shaped notch therein, said carriers having web portions engageable in said V-shaped notches.

5. A machine as called for in claim 4 wherein said V-shaped notches are disposed in a plane generally parallel to said path of travel of the work pieces.

6. In a machine for conveying work pieces with an intermittent motion along a generally straight path by means of rail supported carriers, the combination comprising, a carriage, means for reciprocating the carriage in a direction generally parallel to said path of travel of the work pieces, a plurality of laterally extending arms on the carriage and movable with the carriage, pushers connected to and movable with said arms, said arms being journaled for pivotal movement and said pushers being shifted vertically when said arms are pivoted, said pushers having carrier engaging means thereon movable into and out of engagement with the rail supported carriers in response to vertical movement of the pushers, said carrier engaging means when engaged with said carriers providing a driving connection between the pushers and the carriers whereby to advance the carriers along the rails when the carriage moves through its stroke in one direction, and displaceable means operatively connected with said arms for actuating the same, said displaceable means being timed with the reciprocation of the carriage for pivoting said arms in one direction to engage the pushers with the carriers at one end of the carriage stroke and for pivoting said arms in the opposite direction to disengage the pushers from the carriers at the other end of the carriage stroke.

7. In a plating machine of the type wherein work pieces are conveyed with an intermittent motion through a series of stations in a plating tank by means of rail supported carriers, a combination of a carriage, means for reciprocating the carriage in a direction longitudinally of the tank, a plurality of pusher members on the carriage and movable therewith, said pusher members extending over the tank and being movable in a generally vertical direction on the carriage, said pusher members having means thereon which are engageable and disengageable with the rail supported carriers in response to vertical movement of the pusher members, said carrier engaging means when engaged with said carriers forming a driving connection between the pusher members and the carriers whereby the carriers are moved along said rails when the carriage moves through its stroke in one direction, and displaceable means operatively connected with said arms for actuating the same, said displaceable means being timed with the movement of the carriage for lifting said pusher members to disengage the pusher members from the carriers at one end of the carriage stroke and for lowering said pusher members at the other end of the carriage stroke to reengage the pusher members with the carriers.

8. In a plating machine of the type wherein work pieces are conveyed with an intermittent motion through a series of stations in a plating tank by means of rail supported carriers, the combination of a carriage positioned alongside the tank, means for reciprocating the carriage in a direction longitudinally of the tank, a plurality of laterally extending arms on the carriage movable therewith and extending over said tank, push-

ers connected to and movable with said arms, said arms being journaled for pivotal movement and the pushers being connected thereto so that the pushers are shifted in a generally vertical direction in response to pivotal movement of said arms, said pushers having means thereon which are engageable and disengageable with the rail supported carriers in response to vertical movement of the pushers, said carrier engaging means when engaged with said carriers forming a driving connection between the pushers and the carriers whereby the carriers are moved along said rails when the carriage moves through its stroke in one direction, and displaceable means operatively connected with said arms for actuating the same, said displaceable means being timed with the movement of the carriage for pivoting said arms in one direction to engage the pushers with the carriers at one end of the carriage stroke and to pivot said arms in the opposite direction to disengage the pushers from the carriers at the opposite end of the carriage stroke.

9. A machine as called for in claim 8 wherein said arms are journaled on said carriage for pivotal movement in a generally vertical plane.

10. A machine as called for in claim 8 wherein said arms are journaled on said carriage for pivotal movement in a generally vertical plane extending transversely of the direction of travel of the carriage.

11. A machine as called for in claim 8 wherein said carrier engaging means comprise members on said pushers having downwardly opening V-shaped notches therein, said carriers having upstanding portions engageable by said V-shaped notches when the pushers are moved downwardly toward said carriers.

12. A machine as called for in claim 11 wherein the plane of each V-shaped notch extends generally vertically and in a direction generally parallel to the path of travel of the carriers.

13. A machine as called for in claim 12 wherein said V-shaped notches are provided with an upwardly extending socket at the apex thereof, said carriers having portions thereof shaped to interfit with said sockets to positively locate the carriers relative to the pushers when the pushers are moved downwardly toward the carriers.

14. In a plating machine for conveying work pieces with an intermittent motion through a series of stations in a plating tank by means of rail supported carriers, the combination of a carriage positioned alongside the tank, means for reciprocating the carriage in a direction longitudinally of the tank, a plurality of arms mounted on the carriage for movement therewith and extending over said tanks, pushers connected to and movable with said arms, said arms being journaled on said carriage for pivotal movement in a generally vertical plane extending transversely of the direction of travel of the carriers, said pushers having means thereon which are engageable and disengageable with the carriers in response to vertical movement of the pushers, said carrier engaging means when engaged with said carriers forming a direct driving connection between the pushers and the carriers whereby the carriers are moved along said rails when the carriage moves through its stroke in one direction, a vertically movable elevator structure on said carriage, means for lowering the elevator structure at the forward end of the carriage stroke and for raising said elevator structure at the rear end of the carriage stroke, and means on said elevator structure engageable with said arms for swinging the arms upwardly to cause the pushers to disengage the carriers at the forward end of the carriage stroke and for swinging the arms downwardly at the rear end of the carriage stroke to cause the pushers to engage the carriers.

15. In a machine of the class described which includes a series of treating tanks arranged in a row, the combination of a rail extending longitudinally over the tanks, work carriers slidably arranged on said rail, a carriage extending along the tanks, means for reciprocating the

carriage longitudinally of the row of tanks, pusher members movable with the carriage and selectively engageable with the carriers to advance them along the rail, an elevator structure vertically movable on the carriage, said elevator structure having lift members thereon engageable with the carriers to lift the carriers off the rail when the elevator structure is raised, means for raising the elevator structure at the rear end of the carriage stroke and for lowering the elevator structure at the forward end of the carriage stroke, a plurality of elevated carrier supports above the tank, each of said supports being movable to an operative position wherein it engages and suspends a carrier being lowered by the lift members at the forward end of the carriage stroke and to an inoperative position wherein it is out of the vertical path of travel of the last-mentioned carrier.

16. A machine as called for in claim 15 wherein said carriers are fashioned with flange portions engageable by said lift members and wherein at least some of said lift members are movable to a position wherein the lift members by-pass said flanges of said carriers.

17. The combination called for in claim 15 wherein said pusher members are movably mounted on said carriage for movement to an inoperative position wherein the pushers do not engage the carriers.

18. In a machine of the class described which includes a row of treating tanks divided into successive stations, the combination of a rail extending longitudinally over said row of tanks, work carriers slidably arranged on said rail, a carriage extending along said row of tanks, means for reciprocating the carriage longitudinally of said row of tanks, a plurality of pusher arms on said carriage extending over said rail and supporting pusher members, said arms being pivoted about a generally horizontal axis to raise and lower the pusher members when the arms are pivotally actuated, said pusher members having means thereon engageable and disengageable with the carriers in response to vertical movement of the pusher members, said carrier engaging means when engaged with said carriers forming a direct driving connection between the pusher members and the carriers, an elevator structure vertically movable on said carriage and including lift members engageable with the rail supported carriers to elevate them, means for raising the elevator structure at the rear end of the carriage stroke and for lowering the elevator structure at the forward end of the carriage stroke, each lift members and each pusher member moving from one station to the next station and then back to said one station during a complete cycle of the carriage, means for raising the pusher members out of engagement with the carriers at the forward end of the carriage stroke and for lowering them into engagement with the carriers at the rear end of the carriage stroke, elevated support members at some of said stations, said support members being movable to an operative position wherein a carrier being lowered by said lift members is engaged and suspended above the tanks by the support members and to an inoperative position wherein the support member is out of the vertical path of travel of a carrier on the lift members.

19. A machine as called for in claim 18 wherein said means for raising and lowering said pusher members are carried by said elevator structure.

20. A machine as called for in claim 19 wherein said arms are journaled for pivotal movement on said carriage from a generally horizontal operative position overlying the rail to an inoperative position swung upwardly away from the rail.

21. A machine as called for in claim 18 wherein said pusher members are fixed to move through the same stroke as the carriage, said stations being equally spaced apart.

22. A machine as called for in claim 18 wherein at least some of said lift members are movably mounted on said elevator structure for movement from an operative

position wherein the lift members engage the carriers on the rail when the elevator structure is raised to an inoperative position wherein the lift members by-pass the carriers on the rail when the elevator structure is raised.

23. A machine as called for in claim 18 wherein said carriers include a pair of opposed, generally horizontally disposed and spaced apart flanges, said support members comprising shuttle plates movable in a direction longitudinally of said row of tanks, said elevator structure being arranged to locate the carriers supported by said lift members at the forward end of the carriage stroke so that the said flanges on the carrier overlie the shuttle plate when in operative position, whereby upon lowering of the elevator structure said flanges of the carriers are engaged by the shuttle plates in operative position to sus-

pend the engaged carriers in an elevated position above the tanks.

24. A machine as called for in claim 22 wherein said carriers are provided with a second pair of opposed flanges, said second pair of opposed flanges being disposed in a plane above the plane of said lift members when the elevator structure is in lowered position.
